[57] CLAIM

The ornamental design for a trashcan holder, substantially as shown and described.

DESCRIPTION

FIG. 1 is a front perspective view of a trashcan holder showing my new design;

FIG. 2 is a bottom plan view thereof;

FIG. 3 is a top plan view thereof, with the pipe cap omitted for ease of illustration;

FIG. 4 is a front elevational view thereof, the rear view being substantially a mirror image thereto; and

FIG. 5 is a left side elevational view thereof, the right side being substantially a mirror image thereto.

The central support column has been shown in FIGS. 4 and 5 for clarity of disclosure and ease of illustration.

FIG. 1

FIG. 2

FIG. 3
